(57) **CLAIM**

The ornamental design for a shelf for indoor plant cultivators as shown and described.

DESCRIPTION

FIG. 1 is a front perspective view of the shelf for indoor plant cultivators showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use in which the claimed design is being installed at the inside of the indoor plant cultivators along with the cover.

The broken lines depict portions of the shelf for indoor plant cultivators that form no part of the claimed design. The portions of FIG. 8 drawn in broken lines show environmental structure only and form no part of the claimed design.

1 Claim, 8 Drawing Sheets
